UNITED STATES PATENT OFFICE

2,600,633

CONSTANT VOLUME VARIABLE SPEED
DRIVEN VANE PUMP

Henry C. French, Elm Grove, Wis., assignor to
The Heil Co., Milwaukee, Wis., a corporation of
Wisconsin

Application February 5, 1949, Serial No. 74,758

6 Claims. (Cl. 103—120)

1

This invention relates to improvements in constant volume variable speed driven vane pumps. Vane type pumps, when driven by a variable speed engine, are objectionable in a number of situations because of the fact that variations in the speed of operation of the engine will cause the volume of liquid delivered per unit of time to vary in accordance with the speed of the engine. When this type of pump is used in an hydraulic steering system this objectionable feature is particularly noticeable. The pump is, of course, driven by the same engine which propels the vehicle and must be capable of furnishing suitable hydraulic power for steering regardless of the speed at which the vehicle is being driven, as steering must be done at all speeds. If a tractor is proceeding at very slow speed the volume of oil delivered by the pump for steering purposes may be entirely insufficient to cause steering. On the other hand, for certain uses, a vane type of pump may deliver too great a volume of fluid when the propelling engine is being driven at a high speed.

Vane pumps of the type with which the present invention is concerned are, however, generally desirable for use in hydraulic systems and it is, therefore, a general object of the present invention to provide a structure of the class described which is an improvement over the structure shown and described in my prior application Serial No. 628,435, filed November 14, 1945 and which provides means whereby a substantially constant volume of hydraulic fluid per unit of time is delivered into the pressure line regardless of the speed of the propelling engine or other prime mover.

It is a more specific object of the present invention to provide in a pump of the class described having a rotor formed with floating vanes and having a regulating ring around the vanes, means whereby there is a natural thrust on the regulating ring due to oil pressure in the pump chamber in a direction toward the plunger to thereby make it unnecessary to employ a heavy spring to urge the regulating ring in this direction. Thus during operation of the pump less power is taken to overcome the tension of the spring and there is less possibility of overheating taking place in the discharge duct.

A further object of the invention is to provide a structure as above described wherein there is a differential piston to cause the plunger to normally exert a thrust against the regulating ring in a direction to counteract the natural thrust referred to in the paragraph above.

2

A further object of the invention is to provide a pump where there is thrust bearing means supporting the regulating ring on one side thereof so that pressures will act on the ring in a rectilinear direction only.

With the above and other objects in view the invention consists of the improved vane pump, and all its parts and combinations, as set forth in the claims, and all equivalents thereof.

In the accompanying drawing, illustrating one complete embodiment of the preferred form of the invention, in which the same reference numerals designate the same parts in all of the views:

Fig. 1 is a longitudinal sectional view through the pump casing taken approximately on the line 1—1 of Fig. 2;

Fig. 2 is a sectional view taken approximately on the line 2—2 of Fig. 1; and

Fig. 3 is a diagrammatic view in side elevation showing the pump applied to the hydraulic steering system of a vehicle.

Referring more particularly to the drawing, the numeral 5 designates a main casing portion having a cylindrical pump chamber 6 therein. A drive shaft 7 extends axially of the chamber 6 and its ends are suitably journaled in opposite ends of the casing 5 as at 8 and 9. One end 10 of the shaft projects externally of the casing and may be driven by any suitable source such as the power takeoff 11 from the combustion engine 12 of a vehicle 13 such as a tractor (see Fig. 1).

Rotatable with the shaft 7 and positioned within the chamber 6 is a rotor 14 having its periphery concentric with the wall of the chamber 6.

The periphery of the rotor is formed with angled transversely extending slots 15 for slidably receiving vanes 16, as is customary in a vane type of pump. Surrounding the outer ends of the vanes is a regulating ring 17, the internal diameter of which is substantially greater than the external diameter of the rotor 14.

One peripheral portion of the regulating ring is contacted by a relatively light weight coil spring 18. The latter is accommodated in the hollow stem portion 19 of a screw 20 and the screw is threaded through the wall of the casing 5 and has an exteriorly accessible end so that the pressure exerted on the regulating ring by the spring 18 may be varied.

Positioned approximately 90° from the spring 18 is a carriage 21 having a concave surface portion 22 to fit the peripheral portion of the regulating ring as shown in Fig. 2. The carriage is mov-

able in the directions indicated by the arrows on balls 23 or other anti-friction members. The latter are suitably interposed between the carriage and a supporting block 24. A swingable link 25 which is pivotally associated with both the carriage and block connects the two members. Due to the slotted pivot 26 in the block, rectilineal movement of the carriage on the anti-friction balls 23 is permitted. A suitable cover 27 surrounds the anti-friction balls and said cover may have side loops 28 through which sides of the link 25 pass. The assemblage of the carriage 21, anti-friction members, and block 24 comprises a thrust bearing assembly. The block 24 is connected by bolts 29 or other suitable means with an externally accessible plate 30, and the latter is detachably connected by bolts 31 with a tubular extension 32 of the casing 6.

Opposite the spring 18, the periphery of the regulating ring is engaged by the inner end 33 of a plunger 34.

Oil drawn into the pump through the suction line 35 enters an end of the chamber 6 through an arcuate port 36. This opening is arranged to direct the oil into the space between the rotor and regulating ring and between the vanes as is customary. On the opposite side of the axis of rotation of the rotor from the intake port 36 is an arcuate discharge port 37 which communicates with an outlet passageway 38 leading through a passageway 39 and through an orifice 64 to a reduced pressure fluid chamber 40. It is important to note that the gaps 41 and 42 between the ends of the arcuate ports 36 and 37 are located off of the center lines 1-1 of Fig. 2 about 10°-15°. By this arrangement, the natural thrust on the regulating ring, due to the oil pressure in the pump chamber, extends in the direction indicated by the arrow o, which is at right angles to the center line of the gaps 41 and 42, rather than at right angles to the center line 1-1. Due to the fact that movement toward the left, referring to Fig. 2, is prevented by the carriage 21, the oil thrust indicated by the arrow o is resolved in a rectilineal direction toward the end 33 of the plunger 34. This force, therefore, supplements the force exerted by the spring 18 and eliminates the necessity of using a strong spring.

Connected to a side portion of the casing 5 by bolts 43 is an auxiliary casing 44. The auxiliary casing has a cylindrical pressure chamber 45 one end of which communicates through a bore 46 in the casing 5 with the pump chamber 6. A bore 47 connects the outer end of the auxiliary casing with the other end of the chamber 45 and the bore 47 is in axial alignment with the bore 46, but is of less diameter.

The plunger 34 has an inner portion of a diameter to fit the bore 46 and has an outer portion of reduced diameter to fit the bore portion 47. Piston rings 48 and 49 are positioned in grooves in the plunger portions to form oil seals while permitting reciprocating movement of the plunger. Carried by an intermediate portion of the plunger and positioned within the chamber 45 is a disc-like piston 50 having a peripheral oil sealing ring 51 seated in a peripheral groove in the usual manner. Due to the difference in the diameters of the plunger portions it is obvious that the inner face 52 of the piston has less area than the outer face 53 to create a differential piston arrangement. The plunger is formed with a longitudinal duct 54 which communicates with the outer end of the plunger and also through transverse ducts 55 at its inner end with the pump 75 64 to allow more than a predetermined amount

chamber 6. These ducts open the chamber for the spring 57 to the chamber which surrounds the regulating ring 17 so that the spring chamber is under a negative pressure the same as the chamber which surrounds the regulating ring 17. The latter chamber is under a negative pressure because it is in communication with the line 35 by means of the duct 70 as shown in Fig. 1.

Connected to the outer end of the auxiliary casing portion 44 and projecting therefrom is a cup 56 accommodating a spring 57. The inner end of the spring engages a washer 58 which surrounds a reduced outer end portion 59 of the plunger 34. The spring, therefore, serves to normally urge the plunger inwardly to the position illustrated. The other end of the spring engages a disc 60 and the disc is acted upon by the inner end of an adjustment screw 61. A threaded cap 62 normally covers the projecting end of the adjustment screw. It is apparent that manipulation of the screw 61 will vary the tension exerted by the spring 57 on the plunger 34.

The reduced pressure fluid chamber 40 communicates through an annular duct 63 with that side of the piston chamber 45 which is adjacent the large face 53 of the piston. The chamber 40 is also connected by an orifice 64 of a metering valve with the oil passageway 39.

Threaded into the auxiliary casing 44 is a metering screw 65 which projects through the chamber 40 and which has a conical valve end adapted to cooperate with the orifice 64 to adjustably regulate the volume of fluid delivered per unit of time by the pump into the chamber 40 and out through the outlet line 66 (see Fig. 3).

In use of the pump, the rotor 14 being in operation and the regulating ring being positioned as illustrated in Fig. 2, oil or other hydraulic fluid will be drawn into the pump through the intake port 36 and will be ultimately delivered under pressure into the outlet port 37. During operation the spring 57 will urge the regulating ring toward the eccentric condition illustrated in Fig. 2 in which there is a maximum delivery from the pump.

Where the pump is to be used in a hydraulic steering system 71 of the vehicle 13 (see Fig. 3) the parts are so proportioned and the spring 57 is so adjusted by the screw 61 that the tension of the spring 57 will resist a pressure up to five hundred pounds per square inch acting toward the spring 57. The pressure referred to is that created by the oil in the pump chamber, which as before explained has a natural tendency to urge the regulating ring toward the plunger 34, plus the pressure exerted by the spring 18, plus the pressure exerted by the oil which flows through the bypass 67 to act on the inner face 52 of the piston 50.

The metering valve screw 65 is set to permit flow into the pressure line 68 of a selected volume per unit of time according to the particular requirements. In the example which follows, the valve is set to permit a flow of all the oil that can be moved when the differential in pressure between the pressure in the passageway 39 and that in the chamber 40 does not exceed three hundred pounds.

Assuming that there is 230 pounds per square inch pressure in the passageway 39 and 200 pounds per square inch pressure in the chamber 40 and in the pressure line 66, which differential in pressure is due to the continuous outflow through the line 66, together with the inability of the orifice 64 to allow more than a predetermined amount

to pass into the line 66 per unit of time. The present invention will prevent this pressure differential from substantially exceeding 30 pounds regardless of the speed at which the rotor 14 is being driven. When the rotor is being driven at relatively slow speed, the regulating ring 17 will be maintained in the maximum eccentric position as illustrated. If the speed of the rotor increases, however, the excess pressure in the duct 39 due to the restriction of the orifice 64 will act on the face 52 of the piston 50, and together with the spring 18, will serve to overcome the tension of the spring 57 and move the plunger 34 and piston 50 outwardly toward the spring 57. This movement, however, is always counteracted by the pressure of the oil against the other face 53 of the piston. This pressure acting on the large face 53 will be the pressure existing in the pressure line 66. This pressure will permit outward movement of the piston only a distance which is in direct proportion to the difference in the pressures between that existing in the passageway 39 and that existing in the chamber 40. The net result will be a small movement of the piston outwardly to permit movement of the regulating ring 17 to a less eccentric position and cause a decrease in the pumping action and a decrease in the volume of oil flowing from the pump through the metering valve orifice 64. It is thus apparent that the differential piston 50 will act to always maintain a desired pressure differential between the passageway 39 and the pressure line 66. This will, therefore, result in the delivery of a substantially constant volume by the pump regardless of the speed of the engine 12 which is driving the rotor 14.

By having the gaps 41 and 42 between the ends of the ports 36 and 37 positioned 10°-15° off of the center line 1—1 of Fig. 2 as illustrated, there is a natural oil thrust existing in the space between the rotor 14 and regulating ring 17 tending to aid the spring 18 in moving the regulating ring toward the plunger 34 and against the tension of the spring 57. This natural thrust is due to the fact that there is a greater percentage of the length of the outlet duct 37 toward the plunger 34 so that the discharge pressure of the oil is resolved in a direction to act toward the plunger. Thus a light spring 18 may be used with the result that when the pump is operating normally, less power is taken to overcome the tension of the spring 18. Also there is less tendency for overheating in the discharge duct.

In addition, by having the differential faces on the piston 50, the plunger 34 can exert a thrust against the regulating ring to counteract the thrust caused by the off-center position of the ports 36 and 37. Thus a balance is obtained on the two sides of the piston making a very sensitive arrangement.

By means of the thrust bearing carriage 21, the ring is so supported on one side as to cause all movement due to natural oil thrust to be resolved in a rectilinear direction toward the plunger 34.

Various changes and modifications may be made without departing from the spirit of the invention, and all of such changes are contemplated as may come within the scope of the claims.

I claim:

1. In a vane pump having a rotor provided with inwardly directed peripheral recesses, having a freely rotatable, floating regulating ring normally eccentrically surrounding said rotor, having fluid impelling members movable inwardly and out-

wardly in said rotor recesses with their outer ends engageable with the inner periphery of the regulating ring, and having a casing provided with a pump chamber, there being inlet and outlet ports in an end of said pump chamber, said pump having a discharge duct leading from said discharge port and there being a metering orifice of restricted size interposed in said discharge duct, means for driving said pump at variable speeds, and control means for said regulating ring including a plunger movably engageable with a peripheral portion of said regulating ring, said plunger having differential piston mechanism associated therewith responsive to changes in the pressure differential between the duct portions on the two sides of said metering orifice, and a thrust bearing having a concave part shaped to fit and engageable with a peripheral portion of said ring which is opposite said inlet port, said thrust bearing including a carriage mounted for movement in a direction parallel to the axis of said plunger, the inlet and outlet ports being so located with respect to the axis of said plunger that the discharge pressure of oil in the pump chamber exerts a natural thrust on the regulating ring in a direction to cause movement of the ring and thrust bearing carriage toward the plunger.

2. In a vane pump having a rotor provided with inwardly directed peripheral recesses, having a floating regulating ring normally eccentrically surrounding said rotor, having fluid impelling members movable inwardly and outwardly in said rotor recesses with their outer ends engageable with the inner periphery of the regulating ring, and having a casing provided with a pump chamber, there being an arcuate inlet port in an end of said pump chamber extending for less than 180°, and there being an arcuate discharge port in said end of the pump chamber also extending for less than 180° and of substantially the same length as said inlet port, there being a gap between one pair of adjacent ends of said arcuate ports and there being a diametrically oppositely disposed gap between the other ends of said ports, said pump having a discharge duct leading from said discharge port and there being a metering orifice of restricted size interposed in said discharge duct, means for driving said pump at variable speeds, and control means for said regulating ring including a plunger movably engageable with a peripheral portion of said regulating ring, said plunger having differential piston mechanism associated therewith responsive to changes in the pressure differential between the duct portions on the two sides of said metering orifice, said gaps between the ends of the inlet and outlet ports being so located out of alignment with the axis of said plunger that the discharge pressure of oil in the pump chamber exerts a natural thrust in a predetermined direction, and means for directing movement of the regulating ring which is in response to said thrust toward the plunger.

3. In a vane pump having a rotor provided with inwardly directed peripheral recesses, having a floating regulating ring normally eccentrically surrounding said rotor, having fluid impelling members movable inwardly and outwardly in said rotor recesses with their outer ends engageable with the inner periphery of the regulating ring, and having a casing provided with a pump chamber, there being an arcuate inlet port in an end 75 of said pump chamber extending for less than

180°, and there being an arcuate discharge port in said end of the pump chamber also extending for less than 180° and of substantially the same length as said inlet port, there being a gap between one pair of adjacent ends of said arcuate ports and there being a diametrically oppositely disposed gap between the other ends of said ports, said pump having a discharge duct leading from said discharge port and there being a metering orifice of restricted size interposed in said discharge duct, means for driving said pump at variable speeds, and control means for said regulating ring including a plunger movably engageable with a peripheral portion of said regulating ring, said plunger having differential piston mechanism associated therewith responsive to changes in the pressure differential between the duct portions on the two sides of said metering orifice, and gaps between the ends of the inlet and outlet ports being so located out of alignment with the axis of said plunger that the discharge pressure of oil in the pump chamber exerts a natural thrust in a predetermined direction, a thrust bearing having a carriage engaged by the periphery of said regulating ring, said carriage being mounted for movement in a direction parallel to the axis of said plunger and being positioned to direct movement of the regulating ring which is in response to said thrust, toward the plunger.

4. In a vane pump having a rotor provided with inwardly directed peripheral recesses, having a freely rotatable, floating regulating ring normally eccentrically surrounding said rotor, having fluid impelling members movable inwardly and outwardly in said rotor recesses with their outer ends engageable with the inner periphery of the regulating ring, having a casing provided with a pump chamber, and having a discharge duct leading from said pump chamber, there being a metering orifice of restricted size interposed in said discharge duct, means for driving said pump at variable speeds, means engageable with a peripheral portion of said regulating ring to urge said ring in one radial direction, means engageable with an opposite peripheral portion of said regulating ring to urge the ring in the opposite radial direction and including a differential piston responsive to changes in the pressure differential between the duct portions on the two sides of said metering orifice due to changes in the speed of said driving means for causing said pump to deliver a substantially constant volume of fluid regardless of variations in the driven speed of the pump, and a thrust bearing having a concave part positioned to fit and be engaged by a peripheral portion of the regulating ring which is located intermediate the two regulating ring urging means, said thrust bearing having a rectilinearly movable carriage portion in contact with the regulating ring.

5. In a vane pump having a rotor provided with inwardly directed peripheral recesses, having a regulating ring normally eccentrically surrounding said rotor, having fluid impelling members movable inwardly and outwardly in said rotor recesses with their outer ends engageable with the inner periphery of the regulating ring, having a casing provided with a pump chamber, and having a discharge duct leading from said pump

chamber, there being a metering orifice of restricted size interposed in said discharge duct, means for driving said pump at variable speeds, means including a spring for urging said ring in one radial direction, and means engageable with a peripheral portion of said regulating ring to urge the ring in an opposite radial direction from the direction in which it is urged by said first mentioned means and including a piston having oppositely disposed faces of different area responsive to changes in the pressure differential between the duct portions on the two sides of said metering orifice due to changes in the speed of said driving means for causing said pump to deliver a substantially constant flow of fluid regardless of variations in the driven speed of the pump, there being means on the pump side of said metering orifice affording communication between said discharge duct and the side of the piston chamber adjacent the smaller face of the piston, and there being means on the opposite side of said metering orifice affording communication between the discharge duct and the side of the piston chamber adjacent the larger face of the piston.

6. In a vane pump, a casing having a pump chamber and having a bore communicating with said pump chamber, a rotor rotatable in said pump chamber, vanes projecting from the periphery of said rotor and mounted for inward and outward movement, a regulating ring surrounding said vanes and having its inner periphery engaged by the outer ends of said vanes, a plunger slidably in said casing and having an inner end engageable with a peripheral portion of the regulating ring, resilient means acting on said plunger to normally urge the regulating ring in one radial direction to a position of maximum eccentricity with respect to said rotor, resilient means urging said regulating ring in the opposite radial direction to the direction in which it is urged by said plunger, a piston on said plunger intermediate the length thereof having oppositely disposed faces of different area, there being a piston chamber in said casing within which said piston is movable, said pump chamber having a discharge duct leading therefrom and including a metering orifice, and there being means on the pump side of said metering orifice affording communication between said discharge duct and the side of said piston chamber adjacent the smaller face of the piston, and there being means on the opposite side of said metering orifice affording communication with the side of the piston chamber adjacent the larger face of the piston.
